BASEMENT CLOTHESLINE HANGER

Elbert J. Corpeny, Kansas City, Mo., assignor of
one-half to Carroll J. Klein, Kansas City, Mo.

Application July 5, 1949, Serial No. 103,099

2 Claims. (Cl. 248—324)

1

My invention relates to clothesline hangers, and more particularly to basement clothesline hangers.

It is the principal purpose of my invention to provide a clothesline hanger that is so constructed and arranged that it can be swung from a position depending from a pair of joists to a position in which the entire hanger is located above the bottom edge of the joists. This is possible because there is nothing about the hangers that can engage the joists when swung into a raised position to interfere with such movement thereof. While the clotheslines carried by the hangers would engage the bottom edges of the joists when the hangers are in raised position, the mounting of the clothesline carrying members is such that the clotheslines will flex enough to permit pushing of the entire hanger arrangement up above the bottom edges of the joists with the clotheslines drawn tight along the bottom edges of said joists.

More specifically my invention comprises a clothesline hanger comprising a bar-like member to which the clotheslines are secured, which is mounted on bracket members that are arranged in pairs and secured to adjacent joists so that said bracket members extend obliquely in opposite directions from said joists toward the bar-like member, the diagonal or oblique arrangement of the body portions of said brackets serving to brace the structure so as to provide rigidity for the entire hanger.

Other objects and advantages of my invention will appear as the description of the drawings proceeds. I desire to have it understood, however, that I do not intend to limit myself to the particular details shown or described, except as defined in the claims.

In the drawings:

Fig. 1 is a view in elevation of one of my improved basement clothesline hangers, showing the same attached to a joist, the joist being partly broken away.

Fig. 2 is a transverse sectional view through a plurality of joists, these being partly broken away, showing a pair of my improved basement clothesline hangers in retracted position folded up between the joists and showing the clothesline in a taut or stretched position against the bottom edges of the joists.

Fig. 3 is a fragmentary sectional view showing the mounting of the hanger brackets on a joist, and

Fig. 4 is a view taken at right angles to Fig. 55

1, showing the hanger in end elevation and fragmentary portions of a pair of joists in section.

Referring in detail to the drawings, each of my improved basement clothesline hangers comprises a bar 5, which, preferably, is made of wood, and which, preferably, has openings 6 therein through which a clothesline may be passed for attaching the same to the bar-like member 5. In use two of the brackets are provided, with the bar-like members 5 spaced from each other as shown in Fig. 2. However, in Fig. 2 the hangers are shown in retracted position, as will be explained below, the number of joists intervening between the two spaced bars 5 being merely arbitrarily shown, the number ordinarily being much greater than that illustrated in Fig. 2.

Each of the hanger members further comprises two pairs of brackets, each of said brackets comprising bracket members 7 and 8. Said bracket members 7 and 8 are duplicates, except that the same are reversed in position. Each of said bracket members has an obliquely extending body portion and has an upper end portion 9, which is used for attaching the bracket to a joist 10, said attaching portion extending vertically or parallel to a face of the joist 10. The two bracket members 7 and 8 of a pair are secured to the faces of the joists 10 that are toward each other, and the attachment is made by means of a headed fastening member 11, which is, preferably, a driven fastening of a nail-like character, and preferably, washers 12 are provided between the head of the fastening and the portion 9 of each bracket and between the joists and the portion 9 of each bracket so that the bracket members 7 and 8 can readily be swung from the position shown in Fig. 4 to that shown in Fig. 2.

Each of the brackets 7 and 8 has an attaching portion 13 at the lower end thereof that extends parallel to the portion 9, the portions 13 extending parallel to the side faces of the wooden bar-like member 5, and being secured thereto by means of headed fastening elements, such as the bolts 14, which have heads 15 engaging the attaching portion 13 of a bracket member 8 and which are provided with wing nuts 16 for clamping the parts in assembled position and to exert sufficient tension on the brackets 7 and 8 to create a frictional drag such that the brackets will be held in either a depending position, such as that shown in Fig. 4, or a raised position, such as that shown in Fig. 2. Washers 17 are provided between the vertical faces of the bars 5 and the attaching portions 13, and a lock washer 18 may

be provided between the attaching portion 13 on the member 7 and the wing nut 16.

It will be obvious that each of the hangers comprises a bar-like member 5 and two pairs of brackets 7 and 8, and that when the parts are mounted in position properly between a pair of joists, as shown in Fig. 4, the bar-like member 5 will be located midway between the joists in a position below the same and will be rigidly mounted in its position below the joists because of the diverging arrangement of the body portions of the brackets 7 and 8. It will be further obvious that when the bracket members are swung to the position shown in Fig. 2 the bars 5 will be located in a position parallel to their lowered position, but above the bottoms of the joists 10, and if the line 19 is left in position it will be drawn taut across the bottom of the joists, having enough flexibility that it will extend obliquely from the one joist 10 to which a hanger is secured, at each end of the line, to the bar-like member, as indicated at 20 in Fig. 2.

It will be noted upon reference to Figs. 2 and 4 that the wooden bar 5, which is rectangular in cross section, is located midway between the joists 10 to which the hangers 7 and 8 are attached and remains in that position when swung up between the joists. There is no projecting part on the hanger members that in any way interferes with the movement of the bar from the position shown in Fig. 4 to that shown in Fig. 2, as the only parts that engage the joists are the flat end portions 9, all parts of the brackets 7 and 8 that are secured to the bar 5 being spaced widely from the joists as well as the fastening elements that secure the ends 13 of said brackets to the bar 5.

The attaching means for the lines, being merely holes extending horizontally through the bar-like member, can not in any way interfere with the swinging of the bar-like members 5 upwardly to the position shown in Fig. 2 from that shown in Fig. 4. Also the flat ends 13 on the bracket members 7 and 8 extending parallel to the vertical faces of the bar 5 and being clamped thereto by the bolt and wing nut, will provide frictional resistance to the movement of the bar 5 from one position to another so that the bar will remain in either its raised or lowered position without any necessity of adjusting the clamping means by means of the wing nut 16. However, should there be any tendency for the bar 5 to drop downwardly,

out of the position shown in Fig. 2, it is only necessary to tighten up the wing nut 16 slightly to prevent such movement.

When the hangers are moved to the position shown in Fig. 2 there will be nothing in sight to the casual observer except the parallel lengths of clothesline drawn taut across the bottom sides of the joists, the hanger members being located entirely above said bottom sides of said joists.

What I claim is:

1. The combination with a pair of spaced joists of a bar, and means for mounting said bar midway between said joists for movement between a position below the bottoms of said joists to a position entirely above the bottoms of said joists, comprising hangers pivotally connected with said bar at spaced points and pivotally connected with said joists above the bottom edges thereof, each of said hangers comprising a pair of brackets having obliquely extending portions diverging from said bar toward said joists, each of said brackets having parallel end portions for attachment to said bar and a joist.

2. The combination with a pair of spaced joists of a bar rectangular in cross section, and means for mounting said bar midway between said joists for movement between a position below the bottoms of said joists to a position entirely above the bottoms of said joists, comprising strap metal hangers pivotally connected with opposite flat faces of said bar at spaced points and pivotally connected with the vertical faces of said joists above the bottom edges thereof, each of said hangers comprising a pair of brackets having obliquely extending portions diverging from said bar toward said joists, each of said brackets having parallel flat end portions for attachment to said bar and a joist, the pivotal connections between said brackets and said bar comprising bolts and wing nuts for clamping said pairs of brackets to said bar.

ELBERT J. CORPENY.
